(57) **CLAIM**

The ornamental design for a basket, as shown and described.

DESCRIPTION

FIG. 1 is a perspective view of the basket.

FIG. 2 is a front elevational view of FIG. 1.

FIG. 3 is a rear elevational view of FIG. 1.

FIG. 4 is a left side elevational view of FIG. 1.

FIG. 5 is a right side elevational view of FIG. 1.

FIG. 6 is a top plan view of FIG. 1.

FIG. 7 is a bottom plan view of FIG. 1.

FIG. 8 is a perspective view of the basket shown in use where the each side of the basket is attached by a connector.

FIG. 9 is a front elevational view of FIG. 8.

FIG. 10 is a rear elevational view of FIG. 8.

FIG. 11 is a left side elevational view of FIG. 8.

FIG. 12 is a right side elevational view of FIG. 8.

FIG. 13 is a top plan view of FIG. 8.

FIG. 14 is a bottom plan view of FIG. 8.

FIG. 15 is a perspective view of the basket shown in use where the each side of the basket is attached by another connector.

FIG. 16 is a front elevational view of FIG. 15.

FIG. 17 is a rear elevational view of FIG. 15.

FIG. 18 is a left side elevational view of FIG. 15.

FIG. 19 is a right side elevational view of FIG. 15.

FIG. 20 is a top plan view of FIG. 15; and,

FIG. 21 is a bottom plan view of FIG. 15.

The broken lines showing connectors in FIGS. 8-21 depict environmental subject matter that forms no part of the claimed design.
